[57] CLAIM

The ornamental design for a grip for a portable computing device, as shown and described.

DESCRIPTION

FIG. 1 is a perspective view of a grip for a portable computing device showing our new design, where the top portion of the portable computing device is in a closed position;

FIG. 2 is a top plan view thereof, where the top portion of the portable computing device is in an open position;

FIG. 3 is a top plan view thereof in the closed position;

FIG. 4 is a bottom plan view thereof;

FIG. 5 is a front elevational view thereof;

FIG. 6 is a back elevational view thereof;

FIG. 7 is a right side elevational view thereof; and,

FIG. 8 is a left side elevational view thereof.

The broken line showing of a portable computing device in FIGS. 1–8 are environmental only and form no part of the claimed design.
